UNITED STATES PATENT OFFICE.

OSCAR O. CURTIS, OF FORT MADISON, IOWA, ASSIGNOR TO CURTIS BROTHERS HANDLE COMPANY, OF FORT MADISON, IOWA, A CORPORATION OF SOUTH DAKOTA.

LATHE-REST.

1,316,535.

Specification of Letters Patent. Patented Sept. 16, 1919.

Application filed July 11, 1918. Serial No. 244,418.

To all whom it may concern:

Be it known that I, OSCAR O. CURTIS, a citizen of the United States, residing at Fort Madison, in the county of Lee and State of Iowa, have invented certain new and useful Improvements in Lathe-Rests; and I do hereby declare the following to be a full, clear, and exact description of the invention, such as will enable others skilled in the art to which it appertains to make and use the same:

The present invention relates to improvements in lathe rests, and although the invention may, of course, be found applicable to various different types of lathes, the same has been produced with a view more particularly to its adaptation to the "Defiance automatic handle lathe" manufactured by the Defiance Machine Works of Defiance, Ohio. This Defiance machine is shown and described in United States patent to William A. Kettnering, No. 324,847, granted August 25, 1885, and in the two patents to Peter Kettnering No. 378,322, granted February 21, 1888, and No. 429,924, granted June 10, 1890, reference to which may be had for a more particular explanation of the vibrating table shown in the accompanying drawings in connection with my present invention.

In lathes constructed in accordance with the above mentioned patents and in other lathes to which the present invention is applicable, the stick is operated upon throughout an extended portion of its length by a series of cutters which act simultaneously and cut the stick uniformly either throughout its extended portion or at two points on said stick to which the improved steady rest and the steady rest guides are to be applied.

It is an object of my invention to provide for the support of the work at a relatively weak point thereon, for instance, at a point approximately midway of the lathe centers where the work is subjected to the greatest vibration, due to the action of the cutting knives thereon. To allow such vibration is to permit the work to escape from the knives or saws, with the result that the work is not properly turned.

It is another object of my present invention to enable the long slender flexible sticks, out of which spokes, ax handles, or the like, are made, to be turned smoothly

and quickly without undue vibration. This I accomplish in the manner herein-after more fully described in connection with the accompanying drawings, in which it will be understood I have shown but a single embodiment of which my invention is susceptible.

In the accompanying drawings forming a part of this application, and in which similar reference symbols indicate corresponding parts in the several views:

Figure 1 is a plan view of an improved lathe rest constructed in accordance with the present invention, being shown mounted on the carriage of a Defiance lathe.

Fig. 2 is a rear elevational view of the same; and

Fig. 3 is an end elevational view with parts shown in section.

Referring now more particularly to the drawings, 1 designates the carriage of a Defiance automatic combined spoke and handle lathe which is mounted to vibrate toward and from the cutting knives or saws which are indicated at 2 in Fig. 3. The work or stick is shown at 3, and is held in the usual lathe centers, one of which is shown at 4 in Fig. 1. The work or stick 3 is rotated by the live center in the usual manner, and when the carriage 1 is moved in a left hand direction, as looked at in Fig. 3, said work or stick 3 is brought into engagement with the cutters 2.

The stick or work 3 is shown in Fig. 3 to be supported from beneath by an under work holder 5 and at the side opposite the cutters 2 by a side work holder 6. The side work holder 6 is carried by an arm 7 pivoted, as indicated at 8, in ears 9 on a hanger 10 which carries a set screw 11 forming an adjustable stop for the arm 7, by which the side work holder 6 may be made to assume any normal position with respect to the work 3. The arm 7 carries a weight 12 which normally holds the arm in the position shown in Fig. 3, with the side work holder 6 in contact with the work 3.

A stop 13, carried by the framework of the lathe, is mounted in a position to be engaged by the weight 12. When the carriage 1 is moved to the right, as shown in dotted lines in Fig. 3, the stop 13 arrests the movement of the weight 12 and lower end of the arm 7, causing the latter to be rocked on the pivot 8 so that the upper end of the arm 110

will be carried to the right, with the result that the side work holder 6 is withdrawn from the work.

The hanger 10, above referred to, is slotted as indicated at 14 to adjustably receive a bolt 15 by which it may be fastened to the lathe carriage 1. The parts just described are so mounted on the carriage 1 as to bring the side work holder 6 at a weakened or unsupported part of the work 3, for instance, substantially midway between the lathe centers. At such point the vibration set up in the work 3 by the action of the cutters 2 striking the same, is the greatest, and it is here that the work escapes to the greatest degree the action of the cutters, resulting in the irregular and uneven turning of the stick. The work holder 6 resists this tendency of the work to vibrate, as it supports the work at the side opposite that upon which the cutters 2 are operating.

Near the lathe center 4 I provide a side guide 16 which is mounted on an arm 17 similar to the arm 7 shown in Fig. 3, and similarly mounted to oscillate on a hanger 18 adjustably carried by the table 1. There is a weight 19 also carried by the lower end of this guide arm 17, and a rod 20 passes through registering eyes in the weights 12 and 19; set screws 21 being employed to adjustably hold the ends of the rod 20 therein. By loosening the set screws 21, the arms 7 and 17, together with their associated parts, may be moved farther apart or closer to one another. Through these connections it will be understood that the side work holder 6 is compelled to oscillate in unison with the side guide 16. Such side guide 16 is arranged to bear against a part of the stick 3 which is to be turned similar to that part against which the side work holder 6 engages; but the side guide 16 is disposed very close to one of the centers 4 where the work is supported, and where such work therefore is subject to very slight, if any, vibration.

The said guide 16 will therefore be unaffected by any vibration of the stick and, as it governs the action of the said work holder 6, it will tightly hold the said work holder against an intermediate part of the work which is unsupported and has a tendency to vibrate greatly. At the same time, as the same cross section is to be given the stick 3 at both the points where the side work holder 6 and the side guide 16 engage, any particular pattern may be turned without interference from these parts, as the same may oscillate back and forth about the pivots 8, always bearing effectually against the side of the stick 3.

Referring now to the under work holder 5, the same is preferably mounted as close to the side work holder 6 as practicable, and this under work holder 5 is also movably

supported so that it may follow any particular outline or curvature given to the stick 3, and whereby it may also be depressed away from the stick 3 when the latter is to be removed from or inserted in the lathe 70 centers.

In the embodiment shown in the present drawings, the under work holder 5 is carried on and forms an offset of a round bar 22 slidingly fitted through an opening in a bearing block 23 and adjustably held therein by a set screw 24. A bracket 25 carries a pivot 26 on which the bearing block 23 is adapted to rock; the bearing block 23 and bar 22 forming an oscillating support for 80 the under work holder 5.

Bolts 27 are employed to secure the bracket 25 to the carriage 1, and bolt holes to receive same may be drilled wherever needed through the carriage 1, in order to bring the under 85 work holder 5 at the required position with respect to the work 3. A finger 28 projects from the bar 22, it being adjustably held thereon by a screw 29. The finger 28 is adapted to coöperate with the upper curved 90 end 30 of the weighted arm 7 in a manner to be hereinafter described.

A coil spring 31 is connected between the bearing block 23 and the bent over end of a post 32 adjustable vertically through the 95 bracket 25 and secured in the desired position by a set screw 33. The function of the spring 31 is to yieldingly hold the under work holder 5 against the work 3 and to allow the same to be depressed when required. 100 The screw 34 threaded in the overhanging end 35 of the post 36 forms an adjustable stop to limit the upward movement of the bar 22 when the stick 3 is removed from the lathe centers. At 37 is shown a set 105 screw whereby the post 36 may be vertically adjusted.

In the same way that the side guide 16 governs the movement of the side work holder 6, so the action of the under work 110 holder 5 is controlled by an under guide 38, which is also made to contact with the under side of the stick 3 at a point thereon which is to be turned similar to that part engaged by the under work holder 5; said 115 under guide 38 being also located as close as practicable to the center 4 or at other point along the stick where the same is supported rigidly or is subject to very slight vibration. The under guide 38 may also 120 be formed on the free end of a round bar 39 similar to the bar 22, which bar 39 is adjustably mounted in an oscillating block 40 held on a bracket 41 carried by the carriage 1. This bracket may be adjustable as in the 125 case of the bracket 25.

A stop device 42, which may be similar to that above described in connection with the parts 34, 35, 36 and 37, is associated with the bar 39, and similar spring mechanism in- 130

dicated generally at 43 is provided to yieldingly raise the block 40, bar 39 and guides 16 and 38; these guides being made to bear tightly against the stick near the center 4, 38. Both the blocks 23 and 40 are formed with eyes 44 and 45 to receive the ends of a rod 46 by which the same may be connected, suitable set screws 47 and 48 being provided to adjustably secure these parts together.

The use of the invention may be explained as follows:

The lathe carriage 1 is shown in full lines in Fig. 3 to be in the forward position where the work or stick 3 is in engagement with the cutting knives 2, but before the work 3 is inserted in the centers 4 the carriage 1 is drawn back, for instance, toward the right, as shown in dotted lines. This shifting of the carriage 1 causes the upper end 30 of the oscillating weighted arm 7 to be swung toward the right, as the stop 13 prohibits the movement of the lowered end 12. The side work holder 6 is therefore withdrawn from the stick 3. The under work holder 5 is also, by the same action, removed from its engagement with the work by reason of the fact that the upper end 30 of the arm 7 strikes the projecting finger 28 and depresses the same and the bar 22 which carries it and said under work holder. The spring 31 is drawn out to permit this movement, and when the carriage 1 is returned in the opposite direction, following upon the insertion of a stick to be held in the lathe centers, the said spring 31 will return the under work holder into contact with the freshly inserted stick; the end 30 of the arm 7 being first removed from the finger 28 by the action of the lower weighted end 12, which constantly tends to bring the side work holder 6 against the stick 3.

The parts are now in normal position and the operation of turning the stick 3 is proceeded with.

In the Defiance or other lathe to which this invention may be applicable, the cutters will operate simultaneously and uniformly upon the parts of the sticks 3 at which the steady rests 5 and 6 and the guides 16 and 38 are applied, and said rests and guides will therefore constantly be in contact with, respectively, the sides and under parts of the stick 3.

During the turning of the stick the work holders 5 and 6, which engage at the weakest point, effectually prevent the vibration of such stick in either direction, and prevent the escape of the stick from the effective action of the cutters 2. The result is a uniform and smooth turning. No amount of pressure of the knife cutters is available to set up this vibration in the stick, as the same is opposed by the work holders 5 and 6, which latter are governed in their motions, respectively, by the guides

16 and 38; these guides being made to bear tightly against the stick near the center 4, where such stick is practically without vibration. It is obvious that those skilled in the art may vary the details of construction and arrangements of parts without departing from the spirit of my invention, and therefore I do not wish to be limited to such features except as may be required by the claims.

I claim:

1. In combination with a lathe, a steady rest including yieldable means adapted to hold the work substantially rigid in opposition to the vibration produced by the cutters, said means adapted to be brought in contact with the work at an intermediate point between the lathe centers where the vibration to be governed is great, and means in contact with a similarly turned part of the work near one of the centers and connected to said first named means and adapted to govern the yielding motion thereof, substantially as described.

2. In combination with a lathe, a steady rest including means adapted to engage beneath the work at a point between the lathe centers where the vibration of the work tends to be great, said means being adapted to yieldingly support the work against such vibration, other means correspondingly engaging beneath and at one side of the work at a similarly turned point thereon relatively close to one of the lathe centers where the vibration of the work is very small, and connections between said first and second named means whereby the same may be made to yield in unison substantially as described.

3. In combination with a lathe, a steady rest including means adapted to engage beneath the work, means adapted to engage the side of the work opposite to that operated upon by the cutters, means for yieldingly holding both such first and second named means in contact with the work at a weak point thereon where the vibration is great, an under guide adapted to come in contact with the work at a point thereon where the vibration is small, means whereby said under guide may control the yielding movements of the means for supporting the work from beneath, a second guide adapted to come in contact with one side of the work at a point thereon where the vibration is small, and means whereby said last named guide may be made to govern the yielding movements of said means adapted to engage the side of the work, substantially as described.

4. In combination with a lathe having a vibrating carriage adapted to bring the work into and out of engagement with the cutting knives, a steady rest including under and side work holders adapted to come in

- contact with the work at a point thereon where the vibration is relatively great, means whereby said work holders may be yieldingly supported, means whereby the 5 side work holder may be withdrawn from the work when said vibrating carriage is shifted to remove the work from engagement with the cutting knives, means associated with said side work holder for also 10 withdrawing the under work holder from engagement with the work when the carriage is so shifted, and under and side guides adapted to come in contact with similarly turned parts of the work near to 15 where the work is supported, said guides being connected to said under and side work holders, respectively, whereby to control the motions of the latter, substantially as described.
- 10 5. In combination with a wood working lathe having a vibrating carriage, of a steady rest including a side work holder, a movable arm adapted to carry said side work holder yieldingly into contact with a 20 weak portion of the work, a stop adapted to strike and shift said arm and work holder when the carriage is moved in one direction whereby to withdraw the work holder from the work, guide means in connection with 25 a similarly turned part of the work at a point thereon where the vibration of the work is relatively small, said guide means being connected to control the movements of said arm and side work holder, an under 30 work holder, means supported by said carriage for holding the under work holder yieldingly beneath said work at a point thereon close to said side work holder, means arranged between said arm and last 35
- named means whereby the under work holder may be withdrawn from the work when the carriage is shifted, under guide means in contact with the work near said side guide means, and connections between said under guide means and under work 40 holder for compelling the latter to conform to the motions of the former, substantially as described.
6. In combination with a lathe having a vibrating carriage, of a steady rest including a side work holder, an oscillating weighted arm carrying said side work holder, means for adjustably supporting said arm from said carriage, a stop carried by the lathe and adapted to engage 45 said arm whereby to shift the work holder from engagement with the work, an under work holder, an oscillating support mounted on the carriage for carrying said under work holder, an adjustable finger on said oscillating support adapted to be engaged by one end of said weighted arm whereby to depress the support and under work holder, adjustable yielding means connected to said oscillating support and adapted to 50 bring the under work holder into contact with the work, a stop for said oscillating support, side and under guides mounted in connection with similarly turned parts 55 of the work near where the work is supported, and means for connecting said side and under guides, respectively, to said side and under work holders whereby the same may be made to operate in unison, substantially as described.
- 70 75 In testimony whereof, I affix my signature.

OSCAR O. CURTIS.
